UNITED STATES PATENT OFFICE.

JOHN CHARAVELLE INGRAM, OF CHICAGO, ILLINOIS, ASSIGNOR TO THE AMERICAN COTTON OIL COMPANY, OF NEW YORK, N. Y., A CORPORATION OF NEW JERSEY.

PROCESS OF MAKING SOAP POWDER.

Application filed June 28, 1920. Serial No. 392,451.

To all whom it may concern:

Be it known that I, JOHN C. INGRAM, a citizen of the United States, residing at Chicago, in the county of Cook, State of Illinois, have invented certain new and useful Improvements in Processes of Making Soap Powder; and I do hereby declare the following to be a full, clear, and exact description of the invention, such as will enable others skilled in the art to which it appertains to make and use the same.

This invention relates to the production of a dry soap powder from hot soap paste containing sodium carbonate, and the like.

In the common processes of making soap powders, such as washing and cleaning powders, which contain sodium carbonate or other substances used for the purpose in addition to soap and water, the mass is first cooled, or is allowed to cool spontaneously, to or below the crystallizing point, and is then disintegrated. During the cooling operation, the water contained in the hot soap paste combines with the sodium carbonate to form one or more crystalline hydrates, and the soap paste is, by the crystallization and hydration, converted into a substantially dry state, that is, practically free from uncombined water. Ordinarily, removal of water by evaporation is not necessary or desired, unless the soap paste itself contains an excess of water. That is, the conversion of a soap paste containing sodium carbonate and the like into a dry product is essentially a crystallization and hydration operation, as distinguished from drying by evaporation.

The present invention is distinguished from processes heretofore used for the production of soap powder, from soap paste containing sodium carbonate in that the disintegration of the soap paste precedes the cooling operation, or is effected during the preliminary part of the cooling operation, and the disintegrated soap is obtained directly in the form of a dry powder.

According to the present invention, the hot soap paste containing sodium carbonate and the like as well as soap and water, is subjected to an atomizing or spraying operation, and thereby converted into the form of small particles, and such particles are subjected to the cooling action of a current of air or other suitable gas. The cooling action of the air and the passage of the

particles therethrough are so regulated that the particles are cooled below the temperature of incipient crystallization, so that they are collected in a substantially dry and non-sticking condition. The finely divided particles so obtained can be directly packaged. The improved process of the present invention is well adapted for the production of a dry powder in large quantities and in a continuous manner, even with seasonal variations in weather, such as humidity and temperature.

The invention will be further described in connection with the accompanying drawing showing one form of apparatus adapted for the practice of the invention.

In the accompanying drawing—

Fig. 1 shows, in a somewhat conventional and diagrammatic manner, an arrangement of apparatus adapted for the practice of the invention; and

Fig. 2 is an enlarged view of one form of nozzle.

In the accompanying drawing, a suitable supply tank for the soap mixture is indicated at 1. It may be provided with a slow moving mixer consisting of a number of blades fastened to a horizontal shaft. It is connected at its bottom through a suitable valve control pipe, with the pump 3 by 80 which the soap mixture is forced to the atomizing nozzles 4. A compressed air tank 2 is likewise connected through a pipe, having an air controlling valve 5 therein, with the spray nozzle 4. A pressure gauge 7 is 85 arranged to show the pressure in the nozzle, so that the blowing or atomizing operation can be suitably regulated or controlled. The flow of soap is regulated by the soap valve 6, arranged near the nozzle, and operated by a 90 handle extending through the wall of the atomizing chamber.

The atomizing nozzle 4 is arranged with in a large vertically arranged chamber, and is supplied with a current of air by means of 100 the fan or blower 8 which discharges the air through the passage 9 and opening 10 into the blowing tower. During hot weather the air can be cooled, by suitable cooling means (not shown), such as an air washing system, 105 before it is introduced into the cooling tower, or the air can be otherwise suitably conditioned.

In the operation of the apparatus, the paste or soap mixture is first produced in a 110

hot molten state. This mixture contains, as above noted, soap, water, soda ash, etc., and it may be of compositions such as are commonly used for soap powders containing 5 sodium carbonate, and the like. In general, it is desirable to have a somewhat larger amount of moisture in the paste than is desired in the final dry powder, to make up for such loss of moisture by evaporation as takes 10 place during the spraying and cooling operation.

This paste can be compounded in mixing apparatus such as are commonly used, and the mixed paste can then be supplied to the 15 supply tank 1. This paste can be aerated by beating in air or by treatment with air under pressure during the mixing operation, and the compressed air contained in the soap paste will promote the subsequent spraying 20 operation. So also, further amounts of air can be incorporated in the pump 3, and the soap thereby further aerated before it is atomized, and the atomizing operation correspondingly promoted.

25 Compressed air, from a suitable source, is passed through the air pressure tank 2, where equalization of pressure takes place and where condensed moisture will be trapped, and the compressed air is supplied 30 from this tank at a suitable pressure of, e. g., 75 pounds per square inch, to the atomizing nozzle.

One suitable form of atomizing nozzle is 35 illustrated in Fig. 2 and is made up of the tee 11 to which the air pipe 12 and paste pipe 13 are connected. The discharge is through a spray head 14, of restricted size.

The paste is forced into the spray nozzle 40 against a vertical stream of air entering from the top, and the soap is blown down through the nozzle against the splash disc 15 and is broken up into comparatively small particles. The pressure of the air and the supply of soap are so regulated that the 45 operation is continuous and the desired degree of subdivision is effected. It is important to obtain a proper disintegration and the formation of small particles, and a proper regulation of the cooling operation, 50 so that the particles will be cooled to a temperature below the crystallizing point of the mixture, and so that no large lumps will be permitted to form by collecting the particles before they are properly cooled. The cooling 55 and crystallization should thus be carried to such a point that the powder is not sticky or sufficiently soft to form lumps in the package.

60 The action which takes place in the nozzle illustrated is, as I believe, a jetting action, due to a rapid and intermittent forcing of minute pistons of soap paste outwardly through the nozzle by the air jet, and the further disintegration of these particles by 65 the splash disc. The disintegrating action

is promoted by the rapid expansion of the air escaping from the high pressure to atmospheric pressure, and by the manner in which the air and soap are discharged from the spray nozzle. Referring to Figure 2 it 70 will be seen that the soap is fed into a chamber, the element 11, having a restricted outlet as clearly shown. Because of this restricted outlet, a jetting or pumping action of the nozzle results. The soap is blown 75 against the lower end of the chamber by the blast of fluid under pressure, producing a momentary stoppage or plugging of the outlet. Thus a rapidly alternating series 80 of interruptions and forward movements is produced. The subdivision of the paste is thus effected at the outset of the cooling operation. The particles of soap paste are cooled in their downward passage against the current of air to a temperature such that 85 the desired crystallization and state of dryness is secured. The cooling of the soap paste particles is brought about in part by the expansion of the compressed air from the spray nozzle, in part by evaporation of 90 water from the soap paste particles, which evaporation may amount to from 2 to 5%, in part by radiation, etc.

The powder produced according to the present invention consists of particles or 95 grains of small and fairly uniform size. The size of the particles can, however, be somewhat varied, and may be somewhat larger than would, strictly speaking, be 100 called a powder.

I claim:

1. A method of producing a soap powder, which consists in feeding soap paste and gaseous fluid under pressure to a common chamber having a restricted outlet, in such a 105 manner as whereby to cause the soap to be ejected from the chamber in rapid alternations of stoppage and movement.

2. The method of producing a soap powder, which comprises disintegrating a soap 110 paste, and cooling the disintegrated particles to a temperature below that of crystallization while the particles are suspended in air in a segregated condition, whereby to provide such particles with a surface or skin 115 of dry soap before the particles are massed, to prevent sticking of the particles to each other.

3. The method of producing a soap powder, which comprises atomizing or spraying 120 a soap paste into an upward current of a cooling gas, and effecting the cooling and crystallization of said particles while passing downwardly through said gas and while suspended in such gas in segregated 125 relation whereby to provide such particles with a surface or skin of dry soap before the particles are massed.

4. The method of producing a soap powder, which comprises supplying a soap paste 130

containing sodium carbonate or the like to an atomizing nozzle, disintegrating the soap paste by means of compressed air at such nozzle, thereby subjecting the disintegrated 5 soap particles to a preliminary cooling operation, passing the resulting particles through an upwardly moving stream of cooling gas whereby to surface cool the particles while they are in suspension and in 10 segregated relation, and regulating the operation so that the particles are cooled below the temperature of crystallization while passing through the cooling gas, whereby the particles are obtained in a substantially 15 dry and non-sticking condition.

5. The method of producing a soap powder, which comprises incorporating with soap paste containing sodium carbonate and the like an amount of water in excess of 20 that desired in the soap powder, spraying the resulting paste into a current of a cooling gas, and cooling the particles below the temperature of crystallization and removing the excess water therefrom while passing 25 through the cooling gas, whereby the soap particles are obtained in the form of a substantially dry powder combined with the desired amount of water.

6. A method of producing a soap powder, 30 from soap paste containing sodium carbonate or the like, which consists in subjecting the paste to the action of a jet of fluid under

pressure whereby to disintegrate the paste into relatively small particles, and preliminarily cool the disintegrated particles, passing 35 the disintegrated particles through a current of cooling gas moving in the opposite direction to the particles whereby to delay the particles in their movement and to cool the surface of the particles below the 40 temperature of crystallization, and to provide them with a surface or skin of cooled soap while they are segregated.

7. The method of producing a soap powder, which comprises supplying a soap paste 45 containing basic alkali metal compounds to an atomizing nozzle, disintegrating the soap paste by means of compressed air at such nozzle, thereby subjecting the disintegrated soap particles to a preliminary cooling operation, passing the resulting particles through an upwardly moving stream of cooling gas, whereby to surface cool the particles while they are in suspension and in 50 segregated relation, and regulating the operation so that the particles are cooled below the temperature of crystallization while passing through the cooling gas, whereby the particles are obtained in a substantially 55 dry and non-sticking condition.

In testimony whereof I affix my signature.

JOHN CHARAVELLE INGRAM.
